UNITED STATES PATENT OFFICE

2,209,119

ELECTRICAL TESTING DEVICE

Joseph Ellsworth Hoffman, High Bridge, N. J.

Application May 19, 1939, Serial No. 274,617

1 Claim. (Cl. 175—183)

This invention relates to electrical testing devices, and an object of the invention is to provide a device of this character embodying a flashlight having associated therewith contact means for testing electrical devices, and which will be found handy for such purposes by electricians, radio repair men, electrical inspectors, and others similarly engaged and requiring a quick-testing device.

10 The invention together with its objects and advantages will be best understood from a study of the following description taken in connection with the accompanying drawings wherein:

Figure 1 is a longitudinal sectional view through the device.

Figure 2 is a side elevational view thereof, with the parts arranged when the device is not in use.

Figure 3 is a view taken substantially on the line 3—3 of Figure 2, and

20 Figure 4 is a fragmentary view, somewhat similar to Figure 2 and showing the contact rod extended for use.

Referring more in detail to the drawings, it will be seen that in the preferred embodiment thereof the device comprises a portable electric, well-known type of flashlight 5, the same embodying a cylindrical casing 6 provided at one end with a reflector 7, and a cover 8 having a lens 9 there-in. The reflector is provided with a suitable lamp socket in which is secured an incandescent lamp 10.

The socket portion 7a of the reflector 7 is provided with an integral contact flange 11 with which is electrically engaged, as shown in Figure 3, the contact bar 12 forming part of the flashlight switch indicated generally by the reference numeral 13.

40 The center contact 14 of the bulb 10 is in contact with the center terminal 15 of the two-cell battery, the cells 16—16 of which are connected in series.

On the opposite or other end of the flashlight casing 6 is a screw-threaded cap 17 with which is engaged one end of helical spring 18 which latter is also engaged with the bottom end of one of the battery cells; the cap 17 being screw-threadedly engaged with a peripheral threaded wall 19 of conductive material and to which is riveted or otherwise secured a conductor rod 20' that extends from and forms a part of the casing of the switch 13.

50 Mounted on the periphery of the battery casing 6 and extending longitudinally thereof is an elongated tubular or socket member 20 which houses a sliding contact rod 21. Rod 21 is pro-

vided with a manipulating button 21a, and to accommodate the button 21a, the casing or socket member 20 is provided with a slot 22 which at its opposite end is provided with lateral terminals or extensions 23, 24, to receive the button 21a in a manner to secure the contact rod 21 either in the retracted position shown in Figures 1 and 2, or the extended position shown in Figure 4.

At the upper or closed end thereof the tubular member or socket 20 is provided with an integral contact prong 25 that is in electrical engagement with the contact flange 11 of the lamp socket 7a as best shown in Figure 1.

Mounted on the crown of the cap 17 is a casing 26 in which is housed a spring actuated reel 27, the spring of which is shown at 27' and said reel has wound thereon a tape 28 of metal or other conductive material.

To use the device for testing an electrical apparatus, all that is necessary, as is believed to be obvious, is to project the contact rod 21 locking the same in projected position by engaging the manipulating button 22 thereof with the slot extension 24 as shown in Figure 4; place the contact pin 21 on one part of the electrical circuit or device to be tested, and then extend the element 28 to the desired extent and electrically engage the same with a second part of the circuit or device under test. As a result the circuit through the lamp bulb 10 will, if the device under test is in good working order, be completed to indicate such condition of the device under test. Obviously, should under such circumstances the incandescent bulb 10 fail to light, the user will readily appreciate the fact that the device under test is not in proper working order.

In connection with the above it will thus be seen that through the instrumentality of the contact pin 21 and the member 28, the circuit through the lamp may be completed independently of the switch 13 and that also switch 13 may be operated independently to control the circuit through the lamp bulb.

It is thought that a clear understanding of the construction utility and advantages of an invention of this character will be had without a more detailed description.

Having thus described the invention what is claimed as new is:

A testing attachment for a flashlight comprising an elongated tubular part attached to the case of nonconducting material of the flashlight, a part connected to said tubular member and passing through said case and contacting a part on the lamp socket of the flashlight, said tubular

member having an elongated slot therein formed with angular end parts, a rod for engaging a part of the device to be tested when the rod is projected, said rod being slidably arranged in the tubular member, a pin on the rod sliding in the slot and engaging the annular parts for holding the rod in either projected position or in a position within the tubular member, a housing con-

nected with the metal rear cap of the flashlight, a spring actuated reel in said housing and a metal tape carried by the reel and passing through a slot in the housing, said tape being adapted to be contacted with another part of the device to be tested.

JOSEPH ELLSWORTH HOFFMAN.
